TIRE

Henry D. Bishop, Detroit, Mich., assignor to United States Rubber Company, New York, N. Y., a corporation of New Jersey

Application January 25, 1955, Serial No. 34,241

Term of patent 14 years

(Cl. D90—20)

Fig. 1

Fig. 1 is an elevational view of a tire showing my new design;

Fig. 2 is an enlarged sectional and fragmentary perspective view of the tire showing my new design;

Fig. 3 is a sectional view taken on the line III—III of Fig. 1; and

Fig. 4 is a sectional view taken on the line IV—IV of Fig. 3.

The characteristic feature of the tire design disclosed resides in the combination in a sidewall of a tire of a relatively narrow, circumferentially extending, white band located intermediate the bead and tread of the tire and separated from the bead and the tread of the tire by substantially wider, relatively dark sidewall areas extending respectively from the inner circumference of said white band to said bead and from the outer circumference of said white band to said tread, and circumferentially spaced, rib-like elements extending radially

inwardly from said inner circumference of said white band toward said bead, substantially as shown.

I claim:

The ornamental design for a tire, substantially as shown and described.
